UNITED STATES PATENT OFFICE.

CREGAR B. QUAINSTANCE, OF DENVER, COLORADO.

SHOE-LACE-TIPPING DEVICE.

1,324,745.

Specification of Letters Patent.

Patented Dec. 9, 1919.

Application filed December 17, 1917. Serial No. 207,573.

To all whom it may concern:

Be it known that I, CREGAR B. QUAINSTANCE, a citizen of the United States, and a resident of the city and county of Denver and State of Colorado, have invented certain new and useful Improvements in Shoe-Lace-Tipping Devices, of which the following is a full, clear, and exact description, such as will enable others skilled in the art to which 10 the invention appertains to make and use the same.

My invention relates to improvements in shoe lace tipping devices, and the invention has for its object the provision of a device 15 of this character, which may be conveniently used in stores where shoes and shoe laces are sold, for placing a metal tip on the extremities of shoe laces.

Another object of the invention is to provide a shoe lace tipping device adapted for 20 use in stores or other places where it is frequently necessary to retip a shoe lace.

By way of explanation, the shoe laces are frequently too long, and it becomes necessary to cut off a portion thereof. When this 25 is done, it is necessary to retip the lace, and to this end, this device is adapted to be employed for such retipping.

With these and other objects in view, the 30 invention will now be described with reference to the accompanying drawing which forms a part hereof.

In this drawing, Figure 1 is a view illustrating the retipping device in its entirety; 35 Fig. 2 is a fragment of the retipping device, showing the jaws in position to commence the operation of retipping; Fig. 3 is a view illustrating the jaws in the process of rolling the metal around the extremity 40 of the lace; and Fig. 4 is a view illustrating the jaws in the position occupied by the latter when the operation of retipping has been completed.

Corresponding and like parts are referred 45 to in the following description and indicated in the views of the accompanying drawing by the same reference characters.

The numerals 5 and 6 respectively represent two members of the retipping device, 50 the member 5 having an opening 7 therethrough, through which opening the member 6 is passed. These two members 5 and 6 are pivoted together at their point of intersection, as shown at 8. The member 5 55 is provided at its forward extremity with

an upwardly turned portion 9, which forms one of the jaws of the device. The member 6 at its forward extremity is provided with a part 10, forming another jaw of the retipping device. A metal tip 12 is adapted 60 to be rolled around the extremity of the shoe lace by means of coöperation between the two jaws 9 and 10. This metal tip 12 comprises a sheet of material of the desired length, the same being of such width that 65 it can be rolled entirely around the extremity of the lace. The edge of the sheet 12 is first curved, as shown at 13, and then the sheet is placed against the jaw 9, as shown in Fig. 2 with the extremity 14 of 70 the shoe lace received in the curved portion 13 of the strip 12. Now by causing the two jaws 9 and 10 to come together by gripping the members 5 and 6, the metal strip 12 is rolled around the extremity 14 of the shoe 75 lace. The jaw 10 is provided with a milled surface 15, which prevents said jaw 10 from slipping upon the strip 12, and insures that the said strip 12 will be rolled around the shoe lace. The jaw 9 is provided with a 80 segmental recess 16 and a similar segmental recess 17 is formed at the top of the jaw 10. When the rolling operation of the strip 12 has been completed, these two segmental recesses 16 and 17 receive the metal strip 85 12 therein, as shown in Fig. 1, whereby by applying pressure upon the members 5 and 6, the metal strip 12 may be tightly rolled and packed against the extremity of the 90 shoe lace.

This device is formed entirely of sheet steel whereby the same is rendered comparatively inexpensive in manufacture, and a greater degree of strength and durability is attained.

The jaw 10 is formed by an extension of the member 6 bent in such a way that the said jaw 10 will move parallel with respect to the jaw 9. The jaw 10 has a part 18, which is bent rearwardly and engages with 100 the member 6 whereby the jaw 10 is held rigid.

As illustrated in Fig. 3, means is provided for cutting the tip after the latter has been applied to the lace. In this view, the tip is 105 designated 19. By placing the extremity of this tip 19 in the position illustrated in Fig. 3, between the extremity of the jaw 9 and a cutting surface 20 formed upon the member 5 at the point where the jaw 10 is curved 110

from the latter, there will result a nipping of the extremity of the tip when the latter is engaged therebetween.

While I have described and illustrated 5 herein a specific form of my invention, it is understood that I am not limited thereto, but that the same may be modified or varied without departing from the spirit of the invention or the scope of the appended claim.

10 Having thus described my invention, what I claim and desire to secure by Letters Patent is:—

In a lace tipping device, the combination with intersecting members, one of which is 15 passed through the other one and pivotally connected at their point of intersection, said members having handles for operating the same, two opposing jaws formed on said members and adapted to move in an arc parallel with each other, said jaws adapted to 20

receive a strip of material therebetween, one of said jaws having a milled face adapted to engage said strip of material and the other jaw adapted to hold said strip of material in position so that the one jaw will act upon 25 said strip of material to roll same from one extremity only when said jaws are moved in opposing relation, and said jaws each having a segmental recess, the recess in one jaw receiving the strip of material only when 30 the rolling operation of the latter has been completed, and the two segmental recesses acting in conjunction with each other at the completion of the movement of the jaws in opposing relation for contracting the previously 35 formed convolutions of said strip of material around said lace.

In testimony whereof, I hereunto affix my signature.

CREGAR B. QUAINTANCE.
